UNITED STATES PATENT OFFICE.

ROBERT C. LEWIS, OF LITTLE ROCK, ARKANSAS.

MOISTURE-RADIATOR FOR INCUBATORS.

1,296,197.

Specification of Letters Patent.

Patented Mar. 4, 1919.

Application filed November 20, 1918. Serial No. 263,411.

To all whom it may concern:

Be it known that I, ROBERT C. LEWIS, a citizen of the United States, residing at Little Rock, in the county of Pulaski and State of Arkansas, have invented certain new and useful Improvements in Moisture-Radiators for Incubators, of which the following is a specification.

This invention relates to ventilation, and more especially to air moistening by means of an absorbent surface; and the object of the same is to produce a device for radiating moisture within an incubator contiguous to its egg tray. It is well known that eggs in the act of incubating need a little moisture to simulate that exuding from the mother hen, and especially is this need felt in high altitudes where the air is extremely dry. Hitherto it has been common to place a moisture cup or the like within the incubator so that the heat therein would vaporize the liquid to an extent and cause it to spread over the interior of the entire incubator. My present invention consists in the provision of a sheet of absorbent material mounted directly beneath the egg tray, onto which is poured water, which water evaporates under the influence of the heat within the incubator body. Details are set forth below, and attention is drawn to the drawings, wherein—

Figure 1 is a bottom plan view of an egg tray with this moisture radiator applied.

Fig. 2 is a longitudinal section thereof.

Fig. 3 is an inverted perspective detail of one corner on an enlarged scale.

I have found it necessary to show only one egg tray, omitting even the casing of the incubator which of course surrounds and supports the tray in the usual manner, and omitting also the source of heat which must be and always is present but forms no part of the present invention.

As illustrated herewith, the tray is composed of a rectangular frame 1 having strips 2 across the interior of its ends and along its sides, preferably descending slightly on the sides as shown and overlaid by a central transverse strip 3; and the numeral 4 designates wire fabric mounted within the frame and supported by the strips and on which the eggs are laid. Near one end is a cross strip 5, and a small section 6 of the fabric is hinged upon this cross strip and lies on the nearest end strip 2, thereby forming a

small door through which the hatched chicks may descend as usual. However, the details of construction of the egg tray itself are not important, excepting that its bottom should be of open-work construction, and the wire fabric 4 answers for this purpose.

Coming now to the present invention more particularly, I stretch an absorbent sheet 10 over the entire lower surface of the tray, excepting perhaps that portion of the same occupied by the section or door 6, the sheet being of a width corresponding with the interior of the frame and of a length corresponding with the internal length thereof with the exception of said door. This sheet is preferably of fabric, and I find that rather coarse toweling will answer. It may be hemmed around its edge as indicated at 11 in Fig. 3. Through said edge screw eyes 12 are passed upward into the strip 2 for holding the absorbent sheet in position. As best seen in Fig. 2, the sheet is spaced from the wire fabric 4 a distance equal to the thickness of the strips 2, and when supported by the screw eyes or equivalent fastening devices 12, it will maintain its distance if both are stretched rather taut.

In use, water is poured onto the tray and passes through the wire onto the fabric sheet 10 which by reason of its porous nature will absorb considerable. If the water is poured in before the eggs are in place, it may be cold water; if after the eggs are on the tray, the water is preferably warmed a trifle so as not to chill the eggs. In any event, however, the heat within the incubator body sufficiently warms the water to cause it to throw off moisture which latter rises through the wire fabric 4 and between the eggs on the tray, and permeates all parts of the incubator body. If the fabric is sufficiently heavy, the air will thus be moistened for a long time without the necessity of pouring in more water. Means may be provided for sprinkling the water onto the egg tray, either when the cover of the incubator is open or while it is closed, but as such means form no part of the invention they are not illustrated.

The foregoing description and the drawings have reference to what may be considered the preferred, or approved form of my invention. It is to be understood that I may make such changes in construction and arrangement and combination of parts, materials, dimensions, et cetera, as may prove

expedient and fall within the scope of the appended claims.

Having thus fully described my invention, what I claim as new and desire to secure by Letters Patent is:—

1. In an incubator, the combination with an egg tray comprising a frame of rectangular contour, strips secured around the interior of the frame, and a cross strip within said frame near one end; of a sheet of wire screening secured upon said cross strip and the other strips, a door hinged upon said cross strip and resting at its outer edge upon the adjacent end strip and a sheet of openwork fabric secured to the lower edges of all strips excepting the last-named end strip and lying parallel with said wire screening.
2. In an incubator, the combination with an egg tray comprising a frame of rectangular contour, strips secured around the interior of the frame, and a cross strip within said frame near one end; of a sheet of wire screening secured upon said cross strip and the other strips, a door hinged to said cross strip and resting at its outer edge upon the adjacent end strip, and a sheet of fabric secured to the lower edges of all strips excepting the last-named strip.

regular contour, strips secured around the interior of the frame; a central strip across its center, and a cross strip within said frame near one end; of a sheet of wire screening secured upon said cross strip and the other strips and passing beneath the central strip, a door hinged upon said cross strip and resting at its outer edge upon the adjacent end strip and a sheet of openwork fabric secured to the lower edges of all strips excepting the last-named end strip and lying parallel with said wire screening.

In testimony whereof I affix my signature in presence of two witnesses.

ROBERT C. LEWIS.
